ELECTRIC TORCH

William C. Crimmins, Marion, Ind., assignor to
Sears, Roebuck and Co., Chicago, Ill., a cor-
poration of New York

Application September 21, 1939, Serial No. 295,946

2 Claims. (Cl. 240—7.55)

My invention relates to electric torches of the portable, self-contained battery operating type. My invention is especially adapted for torches or lamps of this type designed for mounting on a vehicle such as a bicycle, automobile, or the like, although it is also adapted for hand use.

A particular object of my invention is to provide an article of the type referred to which will be simple and inexpensive in construction, having a minimum of parts, which is quickly assembled and disassembled, which is strong and secure when the parts are in assembled relation, and which in general will be entirely satisfactory for the purposes desired.

Another object is to provide a device of the type referred to which may be used alternatively as a fog light or headlight.

Various other objects and advantages will suggest themselves to those skilled in the art.

Referring now to the drawing forming a part of this specification and illustrating a preferred embodiment of my invention:

Fig. 1 is a longitudinal view, partly in section and partly in elevation, of a device embodying my invention;

Fig. 2 is a sectional view taken substantially along the line 2—2 of Fig. 1;

Fig. 3 is a plan view showing the inside of one part of the casing; and

Fig. 4 is a plan view of the other part of the casing and parts assembled therewith.

The lamp or torch illustrated comprises a casing formed essentially of two substantially similar interlocking parts 10a and 10b. In the embodiment shown, the casing is of sheet metal and is roughly cylindrical or ellipsoidal or cigar shaped, except for the end which receives the optical unit indicated generally by the numeral 15. It will be understood that the casing may be strictly cylindrical, being shown as tapered for esthetic reasons.

The part 10a comprises a semi-ellipsoidal sheet metal member in the bottom of which is secured, as by rivets 16 or the like, a bracket 18 having a more or less centrally disposed U-shaped portion 19 which is secured to the shell 10a and which serves to space the rest of the bracket therefrom. Secured to the bracket 18, as by spot welding or the like, is a resilient longitudinally disposed sleeve 21, the intermediate portion of which may be cut out as at 22 to increase the resilience thereof as well as to save weight. The bracket 18 terminates in a rearwardly transversely extending spring clip 24 which makes electrical contact with one of the batteries B

and is grounded to the casing 10a. Forwardly, said bracket terminates in an upstanding leg 25. This leg 25 serves to retain an electric bulb 26 and the parts immediately associated therewith, including a sleeve 27 into which the bulb 26 screws, this sleeve having electrical contact with the bracket 18. A reversely bent spring contact clip 28 formed of conducting material is retained in insulated relation on the bracket 18 by means of a rivet 30 or the like, the clip 28 establishing electrical contact with a switch 35 through conductor 36.

The switch 35, also secured in the casing 10a for closing the electrical circuit, may be of standard or other suitable construction and is electrically connected to the lamp as by conductors 39, 39', the lamp socket being grounded to the bracket 18.

Secured to the bracket 18 as by rivets 37 or the like is a U-shaped bracket 40, the web portion of which is apertured to receive a reflector 42 formed of polished metal or other suitable material, said reflector having a flanged collar 43 whereby it is retained in the bracket 40. The polished portion 45 of the reflector is preferably eccentrically arranged, as best seen in Fig. 1, so that with the bulb 26 tilted slightly downwardly, the light beam will be reflected downwardly even though the torch body may be mounted horizontally.

An L-shaped slide member 47 is slidably secured, as by rivets 48 or the like, to the bracket 40, said slide member being slotted as at 49, which slot serves as a track for the rivets 48. The slide member 47 terminates in an upstanding flange 50 which cooperates with a manipulating member in the portion 10b of the casing about to be described. The slider 47 is apertured to receive the bulb socket 27 and a sleeve 52 is secured to said slider so as to be movable longitudinally into and out of a position where it will encircle the bulb 26, as seen best in Fig. 1. It will be understood that when the slider 47 is moved rearwardly, the sleeve 52 will be retracted from a position encompassing the bulb. The sleeve 52 is formed of transparent Celluloid or other suitable material which will serve to diffuse the light emitted from the bulb so that when it is in operative relation to the bulb, as shown in Fig. 1, the light serves as a fog lamp. The forward portion of the casing 10a is indented to form a flange 53 and a slot 54 is provided adjacent the base of said flange for a purpose hereinafter to be described.

The casing 10b is substantially similar in shape

to the portion 10a, being adapted to cooperate therewith to form a completely enclosed unit. The marginal portion of the casing 10b is bent outwardly to form an overlapping flange 55 which overlies the edge of casing 10a. A preferably separate bead or molding strip 56 extends along the flange 55 and is crimped thereover as at 57, as seen best in Fig. 2.

Secured to the forward portion of the casing 10b as by rivets 58 or the like is an annular frame like member 59 which serves to retain a lens 60. The rivets 58 also retain the bead 56. This lens may be of any suitable material but is preferably of a substantially non-shatterable transparent plastic such as a cellulose ester or like synthetic material, and has a flange 61 extending within the ring 59 and retained by fingers 63 which are also secured by the rivets 58.

Slidably mounted in a slot 67 in the casing 10b is a manipulating member 65 carrying, as by means of a rivet 66, a yoke 68 which straddles the flange 50 of the slider 47. A yoke-like member 70 is interposed between the member 68 and the manipulating element 65, this yoke 70 having oppositely disposed flanges 71 on either face of the slot 67 for retaining the parts in slidably assembled relation in the slot 67.

From the above, it is believed that the assembly of the device will be readily understood. Electrical dry cell batteries B, B are disposed within the cradle formed by bracket 18 and sleeve 21, being resiliently retained therein by means of the sleeve and the finger 24, the foremost battery engaging the resilient contact member 28, and the rearmost battery being grounded by contact with finger 24. The part 10b is assembled with the part 10a by first engaging the tongue 73 in the slot 54 and then snapping the two parts together in the position shown in Figs. 1 and 2, the parts being firmly retained by means of a screw 75 at the end thereof. A reinforcing strip 76 may be secured to the part 10a if desired for giving a firm seat to the screw.

A retaining clamp 78 may be secured to the portion 10a as by screws 79 or the like whereby the lamp may be mounted on the frame of a bicycle or in any other suitable place, a buffer strip 80 being provided if desired.

It will thus be seen that I have provided an extremely simple and compact unit which may be produced quite inexpensively, so far as re-

gards labor and materials, being quickly assembled and taken apart for replacing batteries and repairs.

The parts which are frequently found loose in articles of this type, such as, batteries, lens, etc., are firmly retained in my device by simple and inexpensive means, and upon separation of the casing these parts will not spill out. Only a single screw is used for keeping the parts assembled, thus making for quick assembly.

Although I have described my invention as especially applicable to a bicycle light, I do not intend my invention to be so limited, as it is equally applicable for use on other vehicles or for hand use.

Various changes coming within the spirit of my invention may suggest themselves to those skilled in the art and, hence, I do not wish to be limited to the specific form shown or uses mentioned except to the extent indicated in the appended claims, which are to be interpreted as broadly as the state of the art will permit.

I claim:

1. An electric torch comprising a pair of detachable substantially semi-cylindrical interlocking casing members, and means for positively retaining said members in assembled relation, one of said members having means therein for retaining a battery and also having an electric light system including a lamp, a diffusing element associated with the lamp and slidably into and out of operative relation therewith, a member for actuating said diffusing element, and manipulating means on the other casing member detachably engageable with said actuating member.

2. A torch comprising complementary casing shells, a lens frame mounted at an end of one of said shells, a lens mounted in said frame, said shell, frame and lens being movable as a unit, a reflector, battery holder and lighting system including a lamp mounted in and movable as a unit with the other shell, a diffuser movable into and out of cooperative relation with said lens and also movable as a unit with the second shell, means detachably hinging said frame to said second shell for enabling said shells to be swung into and out of operative assembly, and means at the other end of said casing for detachably securing said shells in operative assembly.

WILLIAM C. CRIMMINS.
